(57) CLAIM

The ornamental design for a golf club head cover, as shown and described.

DESCRIPTION

FIG. 1 is a top rear perspective view of our new golf club head cover design;

FIG. 2 is a back view thereof;

FIG. 3 is a front view thereof;

FIG. 4 is a top view thereof;

FIG. 5 is a side view thereof; and,

FIG. 6 is a bottom view thereof.

The portion of the golf club head cover shown in phantom does not form any portion of the present invention.
